UNITED STATES PATENT OFFICE.

NICHOLAS ZUCK, OF ROCHESTER, NEW YORK.

FABRIC FOR GARMENTS.

Application filed March 28, 1921. Serial No. 456,370.

To all whom it may concern:

Be it known that I, NICHOLAS ZUCK, a citizen of the United States of America, residing at Rochester, in the county of Monroe 5 and State of New York, have invented certain new and useful Improvements in Fabrics for Garments, of which the following is a specification.

My invention relates to a fabric for garments and has for its object to afford a laminated fabric structure, which will facilitate the manufacture of coat fronts, and also provide a more durable coat front, characterized at the same time by both pliability 10 and stiffness to the desired degrees.

The invention will be more clearly understood from the following detailed description, in conjunction with the accompanying drawings, the novel features being pointed 20 out in the claims following the description.

In the drawings:

Figure 1 is a plan view of a fabric constructed in accordance with my invention, and

25 Figure 2 is a sectional view on line 2—2 of Figure 1.

For a complete understanding of my invention, I will allude briefly to certain practices in manufacturing coat fronts which are 30 affected by this improvement. A coat front usually includes portions of hair-cloth, felt, and canvas, suitably united, and forming in general a body or side portion, which is connected to the back part of the coat, and a 35 front or lapel portion, which, when the coat is finished, constitutes the open front portion of the coat and also the lapel of the coat.

The felt, or padding material, does not 40 extend beyond the body or side portion of the coat front, and does not form a part of the front or lapel portion. Different grades of hair-cloth are usually employed in the body and lapel portions, the body portion 45 having a stiffer and coarser hair-cloth, and the lapel portion being formed of a finer grade of hair-cloth, to give it somewhat more flexibility.

In constructing and assembling these parts, 50 one practice has been to cut out each material, namely, canvas, coarse hair-cloth, fine hair-cloth, and felt, according to separate patterns. The coarse hair-cloth, forming the body portion, is then sewed to the fine 55 hair-cloth, forming the lapel portion, and

the entire unit is stitched on to the canvas, after which the felt is sewed on.

It is my purpose to eliminate a number of these operations, in addition to affording

a more efficient finished coat front, which is covered in my copending application filed 60 March 28, 1921, Serial No. 456,368, by using only one piece of hair-cloth for both the body and lapel portions, and processing or 65 treating the hair-cloth so that it is thoroughly impregnated with a cementitious stiffening substance, preferably of a waterproofing character. Thus only one pattern is necessary for cutting out the hair-cloth, and no stitching together of two sections of hair- 70 cloth is necessary, so that two operations are saved up to this point.

In order to avoid the necessity of cutting the felt separately, and securing it to the hair-cloth, I first produce a laminated fabric from which the entire hair-cloth and felt unit is formed at one cutting operation, and it is this fabric which 75 constitutes the subject matter of the present application.

The stiffening material or hair-cloth is 80 designated by A and the padding material or felt is designated by B. The hair-cloth A is preferably a fine, closely woven material such for instance as known in the trade as "Hymo", and consisting of cotton or wool 85 woven with mohair or Chinese hair. The hair-cloth is treated, by immersing it in a cementitious stiffening or waterproofing solution, such as rubber cement which is caused to thoroughly permeate every portion 90 of the hair-cloth, giving it more body, greater stiffness, and at the same time the proper pliability which permits it to be rolled or folded, and yet return to its original 95 form.

Following this, the padding material, such as felt, is secured to the hair-cloth, preferably by passing the two thicknesses between pressure rollers, causing the cementitious substance to retain the parts together. The 100 hair-cloth A is wider than the felt B and extends for a considerable distance beyond both edges of the felt strip B. This enables cutting out the entire coat front unit, so far as the hair-cloth and felt are concerned, at 105 one operation and with minimum waste, as the marginal portion of hair-cloth, or that portion beyond the felt, affords the lapel portion of the coat front, while the felt portion extends only as far as the body portion 110

of the coat front. By having the hair-cloth structure extend beyond both edges of the felt, it is possible to lay a coat front pattern either way, and have the lapel portion on either side of the body portion, and in certain classes of garments, it is desirable to have a portion of free hair-cloth on both sides of the felt.

It will be understood that while I have shown only a short section of fabric, it is made in long lengths or rolls, from which the manufacturer will cut his coat fronts as needed. The fundamental advantages of the improvement are that a laminated structure of both stiffening and padding material can be cut from a single pattern at one operation, leaving free portions of the stiffening material on either or both sides of the padding material, without any substantial waste of the latter.

I claim:

1. A fabric for garments comprising a layer of padding material such as felt, and a layer of stiffening material such as hair-cloth affixed to the padding material and of greater width than the padding material.

2. A fabric for garments comprising a layer of padding material such as felt, and a layer of stiffening material such as hair-cloth of greater width than the padding material, the stiffening material being impregnated with a cementitious stiffening substance which also affixes the padding material thereto.

3. A fabric for garments comprising a layer of padding material such as felt, and a layer of stiffening material such as hair-cloth affixed to the padding material, the stiffening material being of greater width than the padding material and impregnated with a cementitious, stiffening substance.

4. A fabric for garments comprising a layer of padding material such as felt, and a layer of stiffening material such as hair-cloth affixed to the padding material, the stiffening material extending laterally beyond both edges of the padding material and being impregnated with a cementitious, stiffening substance.

5. A fabric for garments comprising a layer of padding material such as felt, and a layer of stiffening material such as hair-cloth affixed to the padding material and extending laterally beyond both edges of the padding material.

6. A fabric for garments comprising a layer of padding material such as felt, and a layer of stiffening material such as hair-cloth affixed to the padding material and extending laterally beyond both edges of the padding material, the stiffening material being impregnated with a cementitious stiffening substance which also affixes the padding material thereto.

In witness whereof, I have hereunto signed my name.

NICHOLAS ZUCK.
